[57] CLAIM

[21] Appl. No.: 678,630

The ornamental design for a high speed electroforming system, as shown and described.

[22] Filed: Apr. 1, 1991

DESCRIPTION

[30] Foreign Application Priority Data

FIG. 1 is a perspective view of the design of the high speed electroforming system which is the subject of our invention;

Jan. 23, 1991 [JP] Japan 3-1221

FIG. 2 is a front view thereof;

[52] U.S. Cl. D15/135

FIG. 3 is a right view thereof, the left view being identical;

[58] Field of Search D10/135; 205/73, 67,

FIG. 4 is a rear view thereof;

205/72, 50, 70, 71, 68, 69

FIG. 5 is a top view thereof;

D. 202,924 11/1965 Jacobs D15/135

FIG. 6 is a bottom view thereof; and,

4,696,721 9/1987 Higashino et al. 205/67

FIG. 7 is an alternative perspective view similar to FIG. 1 of our design with the lid open.
